CONTROL MECHANISM FOR CARBURETORS
AND THE LIKE

Robert B. Hyde, Syracuse, N. Y.

Application November 11, 1935, Serial No. 49,277

19 Claims. (Cl. 192—01)

This invention appertains to speed control mechanism and the like, and more particularly, to a carburetor control mechanism especially applicable to motor vehicles.

According to conventional practice at the present time, most motor vehicles are equipped with two control instrumentalities by which the feed of fuel from the carburetor to the cylinders of the motor may be adjusted or regulated. One of these is known as the "hand-throttle" and comprises a pivoted lever on the steering column, or a push-pull knob or other device on the instrument panel or dashboard. The other of these control instrumentalities is known as the "foot-throttle" or accelerator pedal, usually located on the floor adjacent to the brake and clutch pedals. Both of the control devices are connected with a throttle valve forming a part of the carburetor, the former usually by means of a relatively stiff wire or cable, and the latter through a rod or link and associated levers, the details of which vary somewhat in vehicles of different manufacturers.

For the most part, the fuel feed is primarily controlled by the accelerator pedal, and it is only occasionally that the hand-throttle is used, as for example, during starting of the motor, or when setting the vehicle in motion up a grade or an incline, following stopping of the vehicle at the foot of or part way up the incline. The usual throttle valve controls are therefore not very well adapted to afford the best comfort to the driver or operator of the vehicle, particularly on long trips, as in driving the vehicle, one foot must be kept in a more or less fixed position on the accelerator pedal, which, of course, is quite tiring at times. On the other hand, the hand-throttle may be adjusted temporarily to relieve the driver and enable him to remove his foot from the accelerator pedal so as to "rest" the foot and limb. Inasmuch as the throttle valve will remain fixed for any given adjustment of the hand-throttle, it will be readily understood that repeated adjustments of the hand-throttle are required under these conditions, which, of course, is very inconvenient with the conventional control mechanisms now employed, especially if the speed of the vehicle must be reduced suddenly or the vehicle brought to a sudden stop.

One of the primary objects of the present invention is to provide an improved carburetor control mechanism whereby the throttle valve of the carburetor may be manually set to any predetermined position, preferably by means of the conventional hand-throttle, and manually tripped

to restore the control mechanism for conventional operation, preferably incident to depression of the clutch and/or brake pedal. In other words, it has been my aim to afford a means for conveniently adjusting the throttle valve of the carburetor so that the speed of the vehicle will be maintained more or less constant on a relatively level highway, with the further provision for quickly and conveniently restoring the control mechanism for conventional operation, as by means of a manually operable tripping mechanism, preferably controlled by the foot of the vehicle operator.

Another object of the invention is to provide a carburetor throttle valve control mechanism whereby the throttle valve may be manually adjusted to any desired set position, the mechanism including suitable provision for tripping the same at will to restore the throttle valve to its idling position without affecting the set position of the manually adjustable setting means, and having further provision for returning the throttle valve to the original set position without necessitating any readjustment of the manual setting means.

It is a further object of the invention to provide a novel latch means or disconnectible coupling in the throttle control lever system, through means of which the aforementioned objects are attained.

Another object of the invention is to provide a carburetor control mechanism capable of accomplishing the aforementioned ends, without requiring any material modification of the conventional control mechanisms of the various types usually found on motor vehicles of the present day manufacture. In this connection, it is contemplated that my novel mechanism may be installed at the factory during the manufacture of the vehicle, or may constitute an auxiliary attachment for the motor vehicle, adapted to be installed at any time, as desired.

Other and further objects and advantages of the invention will be hereinafter described, and the novel features thereof defined by the appended claims.

In the drawings:

Figure 1 is a side elevation of the master latch unit which forms one of the principal elements of the carburetor throttle valve control, together with the manually operable rocker shaft for tripping the latch unit to restore the throttle valve to its idling position. In this view, the latch unit is shown in a position conforming to a no-load or motor idling condition.

Figure 2 is a view generally similar to Figure 1,

with the trip or rocker shaft omitted, the latch unit being in a position conforming to an adjustment of the hand-throttle to a predetermined position to set the carburetor throttle valve for 5 a given speed; say for example, forty-five miles an hour;

Figure 3 is a view generally similar to Figure 2, but showing the latch unit at the instant of tripping, through actuation of the rocker shaft, 10 and before the control mechanism has had the opportunity to automatically return to the idling or no-load position;

Figure 3—A is a view of the latch unit with the parts in their positions at the completion of 15 the tripping action initially shown in Figure 3.

Figure 4 is a view generally similar to Figure 2, and illustrating the relative positions of the elements of the latch unit under a condition where the foot throttle or accelerator pedal has 20 been depressed to open the carburetor throttle valve beyond the pre-set position of Figure 2, thereby increasing the speed of the vehicle above the forty-five mile per hour set speed, or affording more power for climbing a hill than is afforded by the pre-set position of the hand-throttle and control mechanism;

Figure 5 illustrates a position of the latch unit and associated parts under a condition such as where the vehicle is to be started up a hill 30 or an incline from a standstill, under which condition, the brake and clutch pedals are normally depressed, thereby tripping the latch unit and enabling the hand-throttle to be used in accelerating the motor to start the vehicle into motion, and until the operator's foot is available 35 for operation of the usual accelerator pedal;

Figure 6 is an end elevation of the master latch unit with its parts in the positions illustrated in Figure 1, certain of the parts being 40 broken away and shown in section, and the view illustrating the manner of mounting the latch unit in a convenient position for connection with the carburetor throttle valve;

Figure 7 is a view of the latch unit or assembly 45 generally similar to Figure 1, but illustrating a slightly different arrangement of the parts of the assembly, and particularly, an arrangement wherein the master latch element is positioned at the outside of the unit, that is, superimposed 50 upon the other elements of the unit;

Figure 8 is a detail view in perspective of the 55 elements forming the latch unit, these elements being slightly displaced about from their normally assembled positions to better illustrate the details of the several elements;

Figure 9 is a detail view in end elevation of one suitable form of manually operable tripping mechanism for controlling the rocking of the rocker shaft, which in turn, controls the tripping 60 of the latch unit, the tripping mechanism being illustrated as applied to the usual brake and clutch pedals for actuation of the same by the latter;

Figure 10 is a front elevation of the tripping 65 mechanism shown in Figure 9, as viewed from a point in front of the tripping mechanism and looking rearwardly towards the dash of the vehicle, on which the tripping mechanism is preferably mounted; and

Figure 11 is a fragmentary detail view of 70 certain of the control arms for the rocker shaft, these arms being arranged in pairs, whereby the rocker shaft may be actuated by either the brake or clutch pedal and without interfering with the 75 normal operation of these pedals.

Like reference characters designate corresponding parts in the several figures of the drawings.

Referring first to Figures 1 to 6, inclusive, and Figure 8, my improved control mechanism embodies 5 a latch or disconnectable coupling unit which is composed of a bell-crank lever, generally designated 1, one arm 2 of which is adapted to be connected to the usual throttle valve lever arm 3 of the carburetor 4 as by means 10 of a link or rod 5, and the other arm 6 of which is adapted to be connected to the usual accelerator pedal (not shown) as by means of a link or rod 7. This bell-crank lever is identical with, or similar to, one of the conventional elements 15 of the accelerator control mechanism found on a number of motor vehicles of recent design, and includes a laterally offset portion 8 having an opening 8" for receiving a stud or pin 9 therethrough 20 on which the lever is adapted to be pivotally supported for purposes hereinafter described. This pin or stud 9 may in turn be mounted at any convenient location, as for example, on the intake manifold 10 of the motor, the pin serving 25 as a pivotal axis on which the lever 1 is adapted to rock.

Also pivotally or rockably mounted on the pin 9 is a master latch member or plate 11, having an elongated slot 12 therein through which the 30 pin 9 extends. The plate 11 is provided with a laterally extending arm 13 which is adapted to be operatively connected with the rod 7 of the accelerator control mechanism. For convenience, the arm 13 of the plate 11, and the 35 arm 6 of the bell-crank lever 1 may be provided with registering openings adjacent their outer extremities for receiving therethrough a laterally bent portion 14 on the end of the rod 7, thereby securing these arms to the rod, as will 40 be clear from reference to the drawings. The main body portion 15 of the latch member 11 is substantially circular in form, and is provided adjacent its periphery, substantially opposite to the laterally extending arm 13, with an arcuate 45 slot 16. This slot 16 has the form of two branches 16' and 16'', the former being radially offset respecting the latter so as to provide a shoulder 17 intermediate the opposite ends of slots 16' and 16''. However, the slot 16 may 50 be said to be continuous from the end 18 of branch 16'' to the end 19 of the branch 16'.

Also pivotally mounted on the pin or stud 9 and adjacent to the latch member 11 is a lever arm 20, to the outer extremity of which is suitably connected the hand-throttle cable or wire 21, as at 22. This lever arm 20 carries a pin 23 on a suitably formed extension 24 thereof, the pin 23 extending into the slot 16 of the latch member 11 for purposes which will become more apparent as the description proceeds. This lever arm 20 is generally similar to that found on a number of vehicles of popular make, excepting that these conventional lever arms do not have any pin such as 23, nor is the extension or tongue 24 in the particular form required for the purposes of practicing my invention. However, only a very simple modification of the conventional lever arm is required to adapt the same to use in my improved control mechanism.

In the assembly of the bell-crank lever 1, the latch member 11 and the lever arm 20, onto the pin 9, the member 11 may be and is preferably disposed intermediate the members 1 and 20, as particularly illustrated in Figures 1 to 6, inclusive.

In such an arrangement, the parts may be secured in their assembled position on the pin 9 simply by the use of a cotter pin 25 and without interfering with the operation of the different parts, and particularly, the operation of the member 11 which is loosely mounted on the pin by reason of the provision of the elongated slot 12 in this member. However, if desired, the assembly of the aforementioned parts, which for convenience I have designated the master latch unit, may be as particularly illustrated in Figure 7. In this modified arrangement, the member 11 is outermost, and the bell-crank lever 1 and lever arm 20 are both behind the member 11, with the lever arm 20 intermediate the member 11 and the bell-crank lever. Under these conditions, it will be obvious that the pin 23, carried by the lever 20, projects outwardly through the slot 16, instead of inwardly as in Figures 1 to 6. In each of the foregoing arrangements, the operation of the parts is the same.

The member 11 is provided at one edge thereof with a laterally offstanding tongue or tab 26, the free extremity of which preferably overlies the outer end of the pin or stud 9 for reasons which will shortly become apparent. This tongue or tab 26 serves as an anchor for one end 27 of a coil spring 28, which may be connected thereto, by hooking the end 27 through a suitable opening in the tab or tongue adapted to receive the same. The other end 29 of the spring 28 is anchored to the arm 2 of the bell-crank lever 1, as by hooking this end through an opening in the laterally bent extremity 30 of the rod 5 which connects this arm 2 with the carburetor throttle valve arm 3. Spring 28, when so anchored as mentioned above, is normally under tension so as to normally urge the latch plate 11 towards its pivot pin 9 so that the pin 9 abuts the end 31 of the slot 12. With the latch plate in this position, the slot 16 is so related to the pin 23 that the pin 23 can engage the shoulder 17, which may be recessed slightly if desired to form a seat for the pin and prevent the same from slipping off the shoulder. The position of the parts as just described is best illustrated in Figure 1, and this position may be said to be the idling position, because when the control mechanism is adjusted so that the parts assume the relationship shown in Figure 1, the throttle valve of the carburetor is practically closed and the motor runs at idling speed. However, the throttle valve may be opened by the conventional method to speed up the motor or accelerate the vehicle. In other words, either the hand-throttle or the foot-accelerator may be used in the usual manner to speed up the motor from this idling position of the control mechanism shown in Figure 1.

By way of further explanation of the operation of the master latch unit during operation of the hand-throttle and foot throttle in the customary manner, let it be assumed that the hand-throttle is used to open the carburetor throttle valve. The manual operation of the hand-throttle (not shown) pulls the cable or wire 21, connected at 22 to the end of the lever arm 20, and thus rocks this lever arm in a counter-clockwise direction on the pin 9. Since the member 11 is normally held by the spring 28 in the position shown in Figure 1, with the end 31 of the slot 12 in engagement with the pin 9, the shoulder 17 of the slot 16 is disposed in the path of movement of the pin 23, carried by the lever arm 20, thereby causing the member 11 to rotatably shift on the pin 9 in a

counter-clockwise direction. This shifting of the member 11 in a counter-clockwise direction causes a corresponding shifting of the bell-crank lever 1 in a counter-clockwise direction on the pin 9 because these last mentioned elements have their respective arms 13 and 6 fastened together, as at 14. When the bell-crank lever 1 is rocked in a counter-clockwise direction as just described, the rod 5 is shifted upwardly, being connected to the arm 2, and in turn, the motion of the rod 5 rocks the throttle valve arm 3 upwardly, thus opening the throttle valve.

If the foot-throttle or accelerator pedal is employed to open the carburetor throttle valve farther than its idle position shown in Figure 1, depression of the accelerator pedal actuates the rod 7 to advance the same and cause a counter-clockwise shifting or rotation of the bell-crank lever 1, and hence an upward movement of rod 5, thereby opening the throttle valve to which the upper end of rod 5 is connected. During this actuation of the bell-crank lever 1 by the foot-throttle or accelerator pedal, as just described, the member 11 rocks counter-clockwise on the pivot 9 along with the bell-crank lever, but the lever arm 20 remains stationary, and hence the shoulder 17 moves away from the pin 23. Such a condition can be best understood by reference to Figure 4, although in this figure the hand-throttle has been adjusted so that the lever arm 20 and pin 23 occupy a position corresponding to a speed in excess of idling speed.

It will be understood from the foregoing that the control mechanism, even though including the improved features of my invention, is capable of being operated in the usual manner of operation of conventional throttle valve controls.

Now let it be assumed that the vehicle is in motion and the operator desires to set the throttle valve so the vehicle will be maintained at a substantially constant speed of say forty-five miles per hour. This is readily accomplished by manipulating the hand-throttle so as to pull the wire or cable 21 and rock the lever arm 20 in a counter-clockwise direction. In so doing, the operation of the parts and the result are substantially the same as previously described above in explaining the operation of the latch unit when the hand-throttle is employed to open the carburetor throttle valve. The parts thus assume a position substantially as shown in Figure 2, and so long as the hand throttle is allowed to remain in this set position, the throttle valve will remain set, and hence maintain the speed of the vehicle substantially uniform or constant, assuming that the vehicle is traveling over a substantially level ground. On the other hand, if the vehicle tends to slow down, as it would do when an upgrade is encountered, the operator may return his foot to the accelerator pedal and depress the same further, and thus open the throttle valve further to afford more power. In other words, the throttle valve may be opened beyond the position in which it was originally set by setting the hand-throttle as previously described. This condition is best illustrated in Figure 4. Of course, the throttle valve may be opened wider by further actuation of the hand-throttle, if desired, as will be obvious, and without requiring the operator to depress the accelerator pedal with his foot. On the other hand, if the accelerator pedal has been depressed, so as to open the carburetor throttle valve wider than its initial setting by the hand-throttle control, as is the condition illustrated in Figure 4,

the mechanism will immediately return to the original set position, illustrated in Figure 2, as soon as the operator's foot is removed from the accelerator pedal.

5 By reason of the particular construction and relation of the parts of my master latch unit and associated controls, the carburetor throttle valve may be readily and quickly restored to idling position independently of and without necessitating restoration of the hand-throttle control to its idle position. The mechanism for producing this result, and the operation thereof, will now be particularly described.

Assuming that the control mechanism has been set for a predetermined speed, say forty-five miles an hour for example, by means of the hand-throttle control, this being the condition illustrated in Figure 2, it will be understood that by shifting member 11 transversely on its pivotal axis 9, and against the action of the spring 28, the shoulder 17 will be withdrawn from engagement with the pin 23, as illustrated in Figure 3, permitting the member 11 and bell-crank lever 1 to rock in a clockwise direction on the pivot pin 9, under the influence of the tension spring 32, one end of which is suitably anchored to the arms 13 and 6, as by hooking the end 33 of the spring through a suitable opening in the part 14, the other end of the spring 32 being anchored to some convenient point on the vehicle, as for example, to the dashboard or floor-board. This disengagement of the shoulder 17 from the pin 23, is permitted by reason of the provision of the elongated slot 12 in the member 11, and hence when the member 11 is shifted transversely or laterally respecting the pin 9, the end 36 of the slot engages the pin 9 and limits the transverse shifting movement of the member 11. The action just described may be designated as a tripping action by reason of the fact that the member 11 is released from engagement with the pin 23 and is allowed to rock in a clockwise direction, carrying the bell-crank lever 1 along with it, to a position as illustrated in Figure 3-A, which is the idling position. However, as mentioned above, the lever arm 20 and the pin 23 remain in their pre-set position which has been assumed to be the position in which these parts are shown in Figure 2.

50 In restoring the member 11 and bell-crank lever 1 to idling position, as just described, the pin 23 is received in the branch 16' of the slot 16. Stating this in another way, the branch 16' of the slot 16 registers with the pin 23 when the latch plate is tripped to restore the throttle valve to idling position, and permits the restoration of the throttle valve to idling position under the influence of the tension spring 32. Assuming that the hand throttle control is left in the set position originally assumed, the throttle valve will remain in this idling position until the vehicle operator depresses the accelerator pedal or foot throttle to open the throttle valve, and as soon as the throttle valve has been opened to the point to which the same was originally set, the spring 28 causes the member 11 to shift laterally or transversely respecting the pin 9 to the position with the pin 9 in engagement with the end 31 of the slot 12, thus bringing the shoulder 17 back into engagement behind the pin 23, which is the set position, illustrated in Figure 2, which holds the throttle valve open the desired amount.

Any suitable means may be employed to trip the latch unit so as to permit restoration of the throt-

tle valve to an idling position without necessitating adjustment of the hand throttle. A separate manually operable control lever, pedal, button, or the like, disposed within convenient reach of the vehicle operator's foot or hand, might be utilized for this purpose as desired. However, I preferably employ a mechanism to effect this tripping responsive to a very slight depression of the usual clutch and/or brake pedal. Ordinarily, the clutch and brake pedals may be depressed a substantial amount without materially affecting the parts which they normally control, and hence I am able to avail of this initial movement of the clutch and/or brake as a convenient control for tripping the member 11. To this end, I preferably provide a rocker shaft 40 rockably mounted within the motor compartment of the vehicle, as for example, by means of brackets 41 having bearing portions 42 for receiving the rocker shaft. The brackets may be attached to any convenient support, as for example, to the dash 43 or floor board 44, see particularly Figure 9. The rocker shaft carries a lever arm 45 which is secured thereto in any suitable manner, as by means of a set-screw 46, so as to rock with the shaft 40. Axial movement of the shaft 40 in the bearings 42 may be prevented in any desired manner, as for example, by means of one or more collars 47 adjustably secured to the shaft by the set-screw 48, and the laterally offset spacer 49, formed as a part of the lever arm 45. The free end of the lever arm 45 is yieldably connected with the member 11 by means of a coil spring 50, one end 51 of which is connected to the end of the lever 45, and the other end 52 of which is connected with the free end of the tongue or tab 26 on the member 11. This last mentioned connection between the end 52 of the spring and the tongue 26 is preferably concentric with the pin 9 so that the tension in spring 50 will be maintained uniform in practically all positions of adjustment of the member 11 about the pin 9 as an axis.

The initial tension in spring 50 is practically nil, or at least, less than the tension in spring 28, which acts upon member 11 in a direction substantially opposite to the force exerted by spring 50 when the lever arm 45 is rocked in a clockwise direction (Figures 1 to 7), or a counter-clockwise direction as viewed in Figure 9. The spring 50 is preferably relatively stiff, as compared with spring 28, so as to overcome the tension exerted by the spring 28 when the lever arm 45 and rocker shaft 40 are rocked as just mentioned, and thus insure the tripping of the member 11, as previously described. Shaft 40 and lever arm 45 are normally maintained by any suitable means in a position substantially as illustrated in Figure 1, with no, or very little, tension exerted on spring 50. For this purpose, I preferably provide a coil spring 53, extending about the shaft 40 and having one end fixed thereto as by securing end 54 to the lever arm 45 or its set-screw 46. The opposite end 53 of the spring is extended as at 55, and is adapted to abut against the dash 43 or floorboard 44, so as to urge the rocker shaft 40 and lever arm 45 normally in a direction to relieve the spring 50 of tension. Adjustment in the tension of spring 50 may be taken care of by adjusting the setting of the lever arm 45 on the shaft 40 through means of the set-screw 46.

Any suitable mechanism for actuating the rocker shaft 40 may be employed, as desired. I have found that the arrangement now to be described works quite satisfactorily, and is readily adaptable for use on vehicles of different make.

Fixed to the rocker shaft 40, are a pair of lever arms 56 and 57, preferably adjustably secured to the shaft, as by set-screws 58 and 59. Coacting respectively with these lever arms 56 and 57, are a 5 pair of links 60 and 61, the lower ends of the links being loosely fitted onto the shaft 40 so that the links are free to turn thereon. The links 60 and 61 are adapted to bear against the laterally offset portions 62 and 63 respectively, formed on 10 the upper ends of the arms 56 and 57, whereby rocking motion of one or the other of the links in a counter-clockwise direction about the axis of the rocker shaft 40, as illustrated in dotted lines in Figure 9, will impart a corresponding motion 15 to one of the lever arms 56 or 57, and hence result in a rocking motion being imparted to the shaft 40 for tripping the member 11 of the master latch unit, as previously described. The upper ends of the links 60 and 61 are respectively connected to the brake and clutch pedals, as by 20 means of links or rods 64 and 65, the upper ends of these rods passing through suitable openings in the upper ends of the links 60 and 61, and the lower ends of the rods passing through suitable 25 openings in the pedal extension arms 66 and 67, the latter being secured to the respective brake and clutch pedals 68 and 69, as by means of suitable clamping bands 70 and 71. Clamping of the extension arms 66 and 67 to the brake and clutch 30 pedals is effected through means of the clamping bolts 72 and 73. The free ends of the extension arms 66 and 67 are preferably provided with a plurality of apertures 74, into which the lower end of the respective links 64 and 65 may be selectively received to afford an adjustment of this 35 mechanism so as to provide the desired degree of motion in the various movable parts thereof, and enable the mechanism to be adjusted to the particular vehicle in which the mechanism is installed. As illustrated in Figure 9, a very slight depression of the brake or clutch pedal will effect a substantial rocking action of the rocker shaft 40, and hence trip the member 11 of the master latch unit, as best illustrated in Figure 3. It will also be understood that actuation of the rocker shaft by the depression of the clutch pedal will not affect the brake pedal, owing to the manner in which the arm 56 and link 60, which are associated with the brake pedal 68, are related. In 40 other words, if the rocker shaft 40 is rocked by actuation of the clutch pedal 69, arm 56, with its lateral extension 62, will merely move away from the link 60 which is connected to the brake pedal, and the brake pedal, with its extension arm 45 66 and connecting links 64 and 60, will remain in their normally released position. Similarly, actuation of the rocker shaft 40 by depression of the brake pedal will not affect the clutch pedal. Should both the brake and the clutch pedals be depressed simultaneously, the rocker shaft 40 will be actuated by whichever link mechanism is moved the greatest extent. The torsion spring 53 on the rocker shaft 40 automatically returns the rocker shaft 40 and the arms 56 and 57 carried thereby, to the position illustrated in Figures 9 and 10, as soon as the clutch and brake pedals are released, and thereby conditions the mechanism for further actuation when the clutch and/or brake pedal is depressed. It will be understood that some other form of lost motion linkage may be substituted in lieu of the particular linkages illustrated in Figures 9 to 11.

The mechanism is preferably so designed that if it is desired to use the hand-throttle in starting up from a standstill on a hill, the vehicle

operator may use the hand-throttle in the conventional manner, although it will be necessary to pull the hand-throttle knob or lever farther than usual to open the carburetor throttle valve. This condition is best illustrated in Figure 5. Assuming that the vehicle is at a standstill and the brake pedal is depressed to prevent the vehicle from rolling backwards, with or without the clutch pedal being depressed, according to whether or not the vehicle is in gear, the member 11 will be tripped, as illustrated in Figure 3, this tripping action being effected through the linkage previously described, the rocker shaft 40, the lever arm 45 and the spring 50. The shoulder 17 of the member 11 is thus freed from the pin 23. 15 The hand throttle can then be actuated to rock the lever arm 20 in a counter-clockwise direction on the pin 9 and move the pin 17 through branch 16" of the slot 16 in member 11. As soon as the pin 23 engages the end 18 of the slot 20 16", further rocking movement of the lever arm 20 by manipulation of the hand throttle will shift the member 11 in a counter-clockwise direction and carry the bell-crank lever 1 with it, thus opening the carburetor throttle valve, as will be 25 understood from the previous description of the operation of the latch unit. It will therefore be apparent that the use of my control mechanism does not prevent the operation of the hand and foot-throttles in the ordinary manner of their 30 present day operation. However, my improved mechanism affords a great many advantages over the conventional mechanism, as has been previously explained.

The hand-throttle control may be adjusted to 35 any speed or from any setting to any other setting at any time. When the hand-throttle is availed of to set the latch unit for a given speed, it will remain so set, but it will be understood from the foregoing that the carburetor throttle 40 valve may be practically instantaneously returned to its idling position by a slight depression of the clutch and/or brake pedal through the instrumentalities which have been described. After having tripped the latch unit so as to return the 45 throttle valve to idling position, the throttle valve need not be brought up again to the set speed, but may be actuated in the usual manner through the foot-throttle or accelerator pedal for any degree of adjustment below the set speed. However, as soon as the accelerator is depressed far enough to open the carburetor throttle valve to the extent for which the latch unit was originally set by means of the hand throttle control, the 50 latch unit will automatically become operative to 55 maintain the set speed, although permitting the accelerator to be actuated in the usual manner to increase the speed beyond the set speed, if this is desired. On the other hand, instead of bringing the vehicle up to the set speed by means of 60 the foot-throttle or accelerator pedal, after the latch unit has been once tripped, this can be accomplished by returning the hand-throttle to idling position so as to permit the pin 23 to engage behind the shoulder 17 of the member 11, 65 and then the hand throttle can be actuated to open the carburetor throttle valve again to any desired setting.

While the specific details of the invention have been herein shown and described, the invention 70 is not confined thereto as changes and alterations may be made without departing from the spirit thereof as defined by the appended claims.

What I claim as new, and desire to secure by Letters Patent, is—

1. In a device for controlling the throttle valve of a carburetor or the like, manually operable means for opening the throttle valve, said means including means for maintaining the said throttle valve in open position, and means for rendering said last-named means inoperative to permit the return of the throttle valve to its idling position, said last-named means permitting the throttle valve to be controlled without disturbing the means which normally serves to maintain the throttle valve open.
2. In a device for controlling the throttle valve of a carburetor or the like, manually operable means for opening the throttle valve, said means including means for maintaining the said throttle valve in open position, and means for rendering said last-named means inoperative to permit the return of the throttle valve to its idling position and for restoring the throttle valve to various open positions independently of said manually operable means.
3. In a device for controlling the throttle valve of a carburetor or the like, manually operable means for opening the throttle valve, said means including means for maintaining the said throttle valve in open position, means for rendering said last-named means inoperative to permit the return of the throttle valve to its idling position independently of said manually operable means, and separate manually operable means for restoring said throttle valve to the aforesaid open position independently of the first mentioned manually operable means.
4. In a device for controlling the throttle valve of a carburetor or the like, manually operable control means for selectively opening and closing the throttle valve, said means including means for maintaining the said throttle valve in any desired open position, manually operable means for closing the throttle valve independently of the first-mentioned control means, and means for controlling the throttle valve to an extent less than the desired open position normally maintained by the manually operable control means aforesaid, and without being affected by the latter.
5. In a device for controlling the throttle valve of a carburetor or the like, manually operable control means for selectively opening and closing the throttle valve, said means including means for maintaining the said throttle valve in any desired open position, manually operable means for closing the throttle valve independently of the first-mentioned control means, and means independent of the last-named means and of the means for maintaining the throttle valve in any desired open position for restoring the said throttle valve to the aforesaid open position according to the original setting of the manually operable control means.
6. In a carburetor throttle valve control mechanism for automobiles having the usual brake and clutch control pedals and having a foot-operated control and a hand-operated control for the throttle valve, means operable by the hand control for selectively setting the throttle valve to any desired open position, said means being also actuatable by one of the control pedals aforesaid incident to the depression of the latter, whereby to return the throttle valve to idling position without affecting the hand-operated control, and means actuated by the foot-operated control for returning the throttle valve to the position set by the hand-operated control.
7. In a carburetor throttle valve control mech-
- anism for automobiles having the usual brake and clutch control pedals and having a foot-operated control and a hand-operated control for the throttle valve, means operable by the hand control for selectively setting the throttle valve to any desired open position, said means being also actuatable by one of the control pedals aforesaid incident to the depression of the latter, whereby to return the throttle valve to idling position without affecting the hand-operated control, and said means being operatively connected with the foot-operated control aforesaid whereby to enable the throttle valve to be controlled to a limited extent without being affected by the setting means aforesaid and for restoring the throttle valve to the aforementioned set position incident to actuation of the foot-operated control to a predetermined extent.
8. In a carburetor throttle valve control mechanism for motor vehicles, a manually operable pivotal member having a laterally projecting pin, a pivotal latch member associated with said first member, said latch member having an arcuate slot therein for receiving the pin of the first member and having an abutment shoulder intermediate the ends of said slot adapted to be engaged by said pin so as to cause pivotal movement of said latch member responsive to pivotal movement of said first member, and a third pivotal member operatively connected with the latch member and with the throttle valve whereby to open the throttle valve responsive to manual operation of said first pivotal member to a selectively set position.
9. In a carburetor throttle valve control mechanism for motor vehicles, a manually operable pivotal member having a laterally projecting pin, a pivotal plate member associated with said first member, said plate member having an arcuate slot therein for receiving the pin of the first member and having an abutment shoulder intermediate the ends of said slot normally adapted to be engaged by said pin so as to cause pivotal movement of said plate member responsive to pivotal movement of said first member, a third pivotal member operatively connected with the plate member and adapted to be connected with the throttle valve whereby to enable the throttle valve to be opened responsive to manual operation of said first pivotal member to a selectively set position, and means for shifting said plate member so as to disengage the shoulder from said pin and permit return of the throttle valve to idling position while the manually operable member carrying the pin remains in the selectively set position aforesaid.
10. In a carburetor throttle valve control mechanism for motor vehicles, a manually operable pivotal member having a laterally projecting pin, a second pivotal member associated with said first member, said second member having an arcuate slot therein for receiving the pin of the first member and having an abutment shoulder intermediate the ends of said slot normally adapted to be engaged by said pin so as to cause pivotal movement of said second member responsive to pivotal movement of said first member, a third pivotal member operatively connected with the second member and adapted to be connected with the throttle valve whereby to enable the throttle valve to be opened responsive to manual operation of said first pivotal member to a selectively set position, means for shifting said second member so as to disengage the shoulder from said pin and permit return of the throttle valve to idling position.

tion while the manually operable member carrying the pin remains in the selectively set position aforesaid, and said third member and second member being also manually operable so as to enable the same to be pivotally shifted to re-engage the abutment shoulder with the pin and restore the throttle valve to the set position.

11. In a carburetor throttle valve control mechanism for motor vehicles, a support, a manually operable member pivotally mounted on said support, said member carrying a laterally projecting pin, a latch member pivotally mounted on said support and having an arcuate slot therein for receiving the pin of the first member, said arcuate slot having an offset intermediate its ends forming an abutment shoulder adapted to be normally engaged by said pin so as to cause pivotal movement of said latch member responsive to pivotal movement of said first member, and a bell-crank lever pivotally mounted on said support and having one arm operatively connected with the latch member, and the other arm connected with the throttle valve, whereby to cause the throttle valve to be opened responsive to manual operation of said first pivotal member to a selectively set position.

12. In a carburetor throttle valve control mechanism for motor vehicles, a support, a manually operable member pivotally mounted on said support, said member carrying a laterally projecting pin, a latch member pivotally mounted on said support and having an arcuate slot therein for receiving the pin of the first member, said arcuate slot having an offset intermediate its ends forming an abutment shoulder adapted to be normally engaged by said pin so as to cause pivotal movement of said latch member responsive to pivotal movement of said first member, a bell-crank lever pivotally mounted on said support and having one arm operatively connected with the latch member, and the other arm connected with the throttle valve, whereby to cause the throttle valve to be opened responsive to manual operation of said first pivotal member to a selectively set position, manually operable means operatively connected with the latch member and the first-mentioned arm of the bell-crank lever to effect pivotal movement of the latch member and the bell-crank lever whereby to actuate the throttle valve independently of said first-mentioned manually operable member, and means for normally yieldably urging the latch member, bell-crank lever and throttle valve towards the idling position of the throttle valve.

13. In a carburetor throttle valve control mechanism for motor vehicles, a support, a manually operable member pivotally mounted on said support and carrying a laterally projecting pin, a latch member pivotally mounted on said support and having an arcuate slot therein for receiving the pin of the first member, said arcuate slot being offset intermediate its ends to form an abutment shoulder, said latch member having an elongated slot therein through which said support extends and permitting transverse shifting movement of said latch member on its support, a bell-crank lever pivotally mounted on said support and having one arm operatively connected with the latch member and the other arm operatively connected with the throttle valve, yieldable means intermediate the last-mentioned arm of the bell-crank lever and the latch member for normally urging the latch member transversely respecting its support

whereby to dispose the abutment shoulder in the path of the aforementioned pin and establish an operative connection between the manually operable pin-carrying member and the bell-crank lever to permit opening of the throttle valve responsive to a manual pivotal operation of said first member to a selectively set position, means for yieldably shifting said latch member transversely respecting its support whereby to disengage the abutment shoulder from the pin, and yieldable means for pivotally actuating said latch member and said bell-crank lever on the support when the abutment shoulder is so disengaged from the pin to restore the throttle valve to idling position.

14. In a carburetor throttle valve control mechanism for motor vehicles, a support, a manually operable member pivotally mounted on said support and carrying a laterally projecting pin, a latch member pivotally mounted on said support and having an arcuate slot therein for receiving the pin of the first member, said arcuate slot being offset intermediate its ends to form an abutment shoulder, said latch member having an elongated slot therein through which said support extends and permitting transverse shifting movement of said latch member on its support, a bell-crank lever pivotally mounted on said support and having one arm operatively connected with the latch member and the other arm operatively connected with the throttle valve, yieldable means intermediate the last-mentioned arm of the bell-crank lever and the latch member for normally urging the latch member transversely respecting its support whereby to dispose the abutment shoulder in the path of the aforementioned pin and establish an operative connection between the manually operable pin-carrying member and the bell-crank lever to permit opening of the throttle valve responsive to a manual pivotal operation of said first member to a selectively set position, means for yieldably shifting said latch member transversely respecting its support whereby to disengage the abutment shoulder from the pin, means for pivotally actuating said latch member and said bell-crank lever on the support when the abutment shoulder is so disengaged from the pin to restore the throttle valve to idling position, and manually operable means for restoring the interengagement between the abutment shoulder and the pin and consequently restoring the throttle valve to the aforesaid open position corresponding to the selectively set position of the manually operable pin-carrying member.

15. A carburetor throttle valve control mechanism for automobiles as claimed in claim 13, wherein the yieldable means for shifting the latch member transversely respecting the support to disengage the abutment member from the pin comprises a rocker shaft, a support therefor, a lever arm fixed to said rocker shaft, a spring interposed between the rocker shaft lever arm and the latch member, and manually operable means for actuating said rocker shaft.

16. A carburetor throttle valve control mechanism for automobiles as claimed in claim 13, wherein the yieldable means for shifting the latch member transversely respecting the support to disengage the abutment member from the pin comprises a rocker shaft, a support therefor, a lever arm fixed to said rocker shaft, a spring having one end connected with the rocker shaft lever arm, and its other end operatively connected to the latch member at a point sub-

stantially concentric with the axis of the support on which the latch member is pivotally mounted, and manually operable means for actuating said rocker shaft.

- 5 17. A carburetor throttle valve control mechanism for automobiles as claimed in claim 13, wherein the yieldable means for shifting the latch member transversely respecting the support to disengage the abutment member from the pin comprises a rocker shaft, a support therefor, a lever arm fixed to said rocker shaft, a spring interposed between the rocker shaft lever arm and the latch member, manually operable means for actuating said rocker shaft, said last-named means including a lever arm fixedly mounted on said rocker shaft, a link loosely mounted on said rocker shaft and operatively engageable with said last-mentioned lever arm intermediate its ends, and means adapted to be attached to one of the brake or clutch pedals and having operative connection with the free end of said link whereby to rock said link on said rocker shaft and impart a rocking motion to said rocker shaft pursuant to engagement of said link with its associated rocker shaft lever arm responsive to depression of the aforesaid pedal.
- 10 18. A carburetor throttle valve control mechanism for automobiles as claimed in claim 13, wherein the yieldable means for shifting the latch member transversely respecting the support to disengage the abutment member from the pin comprises a rocker shaft, a support therefor, a lever arm fixed to said shaft, a spring interposed between the rocker shaft lever arm and the latch member, manually operable means for actuating said rocker shaft, said last-named means including a pair of laterally spaced lever arms fixedly mounted on said rocker shaft, a pair of links loosely mounted on said rocker shaft and laterally spaced apart so as to respectively im-

parting rocking motion thereto responsive to rocking movement of the respective links, and means adapted to be attached to the usual brake and clutch pedals of the automobile, and operatively connected with the aforesaid links whereby to selectively impart a rocking motion to the latter responsive to depression of one or the other of the aforesaid brake and clutch pedals, and consequently produce a rocking of said rocker shaft.

- 15 19. An attachment for carburetor throttle valve control mechanisms in motor vehicles, comprising a manually operable member having provision for pivotally mounting the same on a support, said member carrying a laterally projecting pin, a plate member also having provision for pivotally mounting the same on the support so as to enable transverse shifting of the same on the support as well as rotative shifting about the support, said plate member being provided with an arcuate slot therein for receiving the pin of the first member, said arcuate slot being offset intermediate its ends to form an abutment shoulder, a bell-crank lever having provision for pivotally mounting the same on the support and having one arm disposed for operative connection with the plate member, and the other arm adapted to be operatively connected with the throttle valve, yieldable means intermediate the last-mentioned arm of the bell-crank lever and the plate member for normally urging the plate member transversely shifted respecting its support whereby to dispose the abutment shoulder in the path of the aforementioned pin and establish a releasable operative connection between the manually operable pin-carried member and the bell-crank lever, and means operable at will for shifting said plate member transversely respecting its support to prevent engagement of the shoulder with the pin.
